UNITED STATES PATENT OFFICE

HENRY GARVEY, JR., OF ST. FRANCISVILLE, ILLINOIS

THEFT ALARM

Application filed January 3, 1930. Serial No. 418,299.

The present invention relates to a theft alarm adapted for use on chicken coops and in other places and has for its prime object to provide means whereby when a door 5 is opened by an unauthorized person a report or signal will be sounded.

Another very important object of the invention resides in the provision of an apparatus of this nature wherein the turning of 10 the knob on a door will release a hammer for igniting a cartridge so as to sound a report signalling an unauthorized opening or attempt to open the door.

A still further very important object of the 15 invention resides in the provision of an apparatus of this nature which is exceedingly simple in its construction, inexpensive to manufacture and install, strong and durable, thoroughly efficient and reliable in use and 20 operation, otherwise well adapted to the purpose for which it is designed.

With the above and numerous other objects 25 in view as will appear as the description proceeds, the invention resides in certain novel features of construction, and in the combination and arrangement of parts as will be hereinafter more fully described and claimed.

In the drawing: 30 Figure 1 is an inner elevation of a door frame and door showing a wall of a building in section with my improved apparatus mounted in place,

Figure 2 is an outside elevation of the door, 35 Figure 3 is a vertical sectional view taken substantially on the line 3—3 of Figure 1,

Figure 4 is a sectional view taken substantially on the line 4—4 of Figure 1,

Figure 5 is a sectional view taken substantially on the line 5—5 of Figure 2,

Figure 6 is an end view of the tube,

Figure 7 is a sectional view taken substantially on the line 7—7 of Figure 3, and

Figure 8 is a sectional view taken substantially on the line 8—8 of Figure 1.

Referring to the drawings in detail it will be seen that the numeral 5 denotes a door frame, the numeral 6 a door and the numeral 7 a wall. A knob 8 is mounted on the inside of the latch mechanism 9 of the door. A 50 barrel 10 is mounted vertically on the lower portion of the door by suitable bracket 11 and the bottom end of the barrel is threadedly engaged with an elbow 12 extending through an opening in the bottom of the door 55 as is clearly illustrated in Figure 3.

A union 14 is threadedly engaged with the upper end of the barrel. A tube 15 is threadedly engaged with the union and extends up through a bracket 16 on the intermediate portion of the door. 60

An elongated hammer bar 17 is slidable in the tube through a guide bracket 18 at the top of the door and when in its uppermost position the top end of this bar extends into 65 a notch 19 formed in the upper part of the frame 5.

A striker 20 is slidably mounted in the lower end of the tube and is adapted to be actuated by the bar 17 as the same gravitates 70 downwardly as will be explained later. The bar is provided with an opening 21 therethrough so that a pin may be inserted through an opening 23 in the door through this opening to hold the bar in a raised position for 75 the purpose of unscrewing the tube 15 so that a cartridge 24 may be inserted in the barrel.

The pin used for this purpose is disclosed at 26. Normally, however, the bar is held in a raised position by a pin 27, the outer 80 end of which is in the form of an eye for receiving hook 28 pivotally engaged on a threaded rod 29 threadedly engaged in the fork 30 which is engaged on the knob by means of a cotter pin 31 or the like so that 85 when the knob is oscillated from the inside or outside the pin 27 will be withdrawn thereby allowing the hammer bar 17 to gravitate downwardly, impinge against the striker 20 which will shut off the compression cap of 90

the cartridge 24 firing the same which, of course, will tend to scare off the unauthorized person and will render a loud report.

In order that an authorized person may open the door without causing the signal to be given, a cable 40 is engaged with the hook 28 and trained over pulleys 31 and through a tube 42 extending through an opening in the wall 7 at some secret point. A ring 43 is 10 preferably provided on the end of the cable so that this cable may be pulled to disengage the hook 28 from the eye of the pin 27 therefore the door may be readily opened without firing the cartridge.

15 It is thought that the construction, operation, utility and advantages of this invention will now be quite apparent to those skilled in this art without a more detailed description thereof.

20 The present embodiment of the invention has been disclosed in considerable detail merely for the purposes of exemplification since in actual practice it attains the features of advantage enumerated as desirable in the 25 statement of the invention and the above description.

It will be apparent that changes in the details of construction, and in the combination and arrangement of parts may be 30 sorted to without departing from the spirit or scope of the invention as hereinafter claimed or sacrificing any of its advantages.

Having thus described my invention, what I claim as new is:

35 1. An apparatus of the class described comprising a barrel adapted to receive a cartridge in the upper end thereof, a union engaged with the barrel, a tube detachably engaged with the union, a hammer bar slideable in the tube, a striker in the bottom of the 40 tube adapted to be impinged against by the hammer for igniting the cartridge, and means for holding the hammer raised.

45 2. An apparatus of the class described comprising a barrel adapted to receive a cartridge in the upper end thereof, a union engaged with the barrel, a tube detachably engaged with the union, a hammer bar slideable in the tube, a striker in the bottom of the 50 tube adapted to be impinged against by the hammer for igniting the cartridge, and means for holding the hammer raised, means for mounting the barrel and the tube on the inside of a door, and an elbow connected with the bottom of the barrel and extending through an opening in the door.

55 3. An apparatus of the class described comprising a barrel adapted to receive a cartridge in the upper end thereof, a union engaged with the barrel, a tube detachably engaged with the union, a hammer bar slideable in the tube, a striker in the bottom of the tube adapted to be impinged against by the hammer for igniting the cartridge, and 60 means for holding the hammer raised, means 65

for mounting the barrel and the tube on the inside of a door, and an elbow connected with the bottom of the barrel and extending through an opening in the door, said means for holding the hammer comprising a pin extending through the tube, and a knob actuated means for pulling the pin out to release the hammer. 70

4. An apparatus of the class described comprising a barrel adapted to receive a cartridge in the upper end thereof, a union engaged with the barrel, a tube detachably engaged with the union, a hammer bar slideable in the tube, a striker in the bottom of the tube adapted to be impinged against by the hammer for igniting the cartridge, and means for holding the hammer raised, means for mounting the barrel and the tube on the inside of a door, and an elbow connected with the bottom of the barrel and extending through an opening in the door, said means for holding the hammer comprising a pin extending through the tube, and a knob actuated means for pulling the pin out to release the hammer, said tube having an opening therein, said door having an opening therein, and a pin adapted to be extended through said opening into an opening in the barrel to hold the same in a raised position while the tube is being detached for reloading purposes. 80

5. An apparatus of the class described comprising a barrel adapted to receive a cartridge in the upper end thereof, a union engaged with the barrel, a tube detachably engaged with the union, a hammer bar slideable in the tube, a striker in the bottom of the tube adapted to be impinged against by the hammer for igniting the cartridge, and means for holding the hammer raised, means for mounting the barrel and the tube on the inside of a door, and an elbow connected with the bottom of the barrel and extending through an opening in the door, said means for holding the hammer comprising a pin extending through the tube, and a knob actuated means for pulling the pin out to release the hammer, said knob actuating means comprising a pivoted hook operatively engaged with the knob and engageable with an eye 100 formed on the pin. 105

6. An apparatus of the class described comprising a barrel adapted to receive a cartridge in the upper end thereof, a union engaged with the barrel, a tube detachably engaged with the union, a hammer bar slideable in the tube, a striker in the bottom of the tube adapted to be impinged against by the hammer for igniting the cartridge, and means for holding the hammer raised, means for mounting the barrel and the tube on the inside of a door, and an elbow connected with the bottom of the barrel and extending through an opening in the door, said means for holding the hammer comprising a pin ex- 110 115 120 125 130

tending through the tube, and a knob actuated means for pulling the pin out to release the hammer, said knob actuating means comprising a pivoted hook operatively engaged with the knob and engageable with an eye formed on the pin, a cable engaged with the hook, pulleys over which the cable is trained, and a tube through which the cable is trained, said tube being adapted to terminate at a secret point so that the cable may be pulled for disengaging the hook from the pin for authorized opening of the door.

In testimony whereof I affix my signature.

HENRY GARVEY, JR.
